UNITED STATES PATENT OFFICE.

MANFRED FISCHHABER, OF NEW YORK, N. Y.

HAIR-CRIMPER.

SPECIFICATION forming part of Letters Patent No. 629,157, dated July 18, 1899.

Application filed September 30, 1898. Serial No. 692,261. (No model.)

To all whom it may concern:

Be it known that I, MANFRED FISCHHABER, a citizen of the United States, residing in the city, county, and State of New York, have invented a new and useful Improvement in Hair-Curlers, which improvement is fully set forth in the following specification and accompanying drawings.

My invention relates to an improved construction of hair-curler, the same being designed as an improvement upon a prior patent granted to me and consisting of a plurality of members, one of which has arc-shaped or curved limbs of unequal length and joined by a cross-bar upon which is pivotally hinged or supported the other member of the curler upon which the hair is to be wound.

It further consists in the provision of means whereby the curler can be readily drawn from the hair without necessitating unwinding of the latter therefrom.

It further consists of novel details of construction, all as will be hereinafter fully set forth, and particularly pointed out in the claim that follows the specification.

Figure 1 represents a plan view of a hair-curler embodying my invention, the same being shown in open position. Fig. 2 represents a plan view similar to Fig. 1, but showing a member of the curler having hair wound thereupon. Fig. 3 represents a plan view of the curler having hair wound thereupon and shown in closed or operative position. Fig. 4 represents a side elevation of Fig. 3.

Similar letters of reference indicate corresponding parts in the figures.

Referring to the drawings, A designates a hair-curler, the same consisting of the inner and outer members B and C, which are composed of suitable resilient material. The member C is composed of the limb D, which is curved or arc-shaped, and of the limb E, which is also curved and has the portion F, which is extended past the axial line a of the curler and beyond the terminal G, said portion F ending with the reversely-curved and longitudinally-extended terminal H, whereby a space J is formed between said terminals and an extended and smooth curved surface and is presented by the terminal H for contact with the curled hair when the curler is with-

drawn, said limbs D and E being joined by the cross-bar K. The inner member B of the curler consists of the limbs L, which are joined by the helical or spiral convolution or coil M, 55 the latter encircling the cross-bar K, whereby the limbs B and C are movably or pivotally connected to each other.

The operation is as follows: The hair is wound upon the member B of the curler in 60 the manner indicated in Figs. 1 and 2, after which the parts are turned into the position indicated in Fig. 3. It will be noted that by reason of the substantially oval or elliptical space between the limbs D and E the latter 65 will not contact with the hair, and by the provision of the portion or extension F the latter forms an abutment which can be sprung under the free ends of the member B, as shown in Fig. 3, and by reason of the open space J 70 the whole curler can be withdrawn at once from the hair when the parts are in the position seen in Fig. 3, the hair readily passing the terminals G and H in the act of withdrawal, as is evident, it being noted that 75 the space between these terminals permits such operation, while when the device is in the position shown in Fig. 3 said limbs hold the same firmly in such position. The terminal H of the long limb E is reversely 80 curved to present an extended and smooth curved surface on the side thereof adjacent the tuft of hair wound upon the inner member B to facilitate the withdrawal of the device, it being noted that as the curler is withdrawn the curved longitudinally-extended 85 terminal H slides easily and readily over the tuft of hair, as is obvious. Attention is also called to the fact that the curler can be operated from both sides, right or left, and the 90 ease by which it can be withdrawn from the hair and turned into the closed operative position (seen in Fig. 3) without springing the limbs E D over the hair or necessitating any contact therewith while in this position renders the present device an important improvement over devices heretofore constructed in accordance with the prior art.

Having thus described my invention, what I claim as new, and desire to secure by Letters 100 Patent, is—

A hair-curler, consisting of inner and outer

limbed resilient members, pivotally connected, the limbs of the outer member being unequal in length, the short limb being situated entirely on one side of the inner member, and 5 the long limb extending across the axis of the curler and terminating beyond the end of the short limb with a longitudinally-extended end

portion to provide a space between the same and the end of the short limb.

MANFRED FISCHHABER.
